UNITED STATES PATENT OFFICE.

CARL CHRISTIANSON, OF DEERFIELD, WISCONSIN.

WAGON.

1,279,839.

Specification of Letters Patent. Patented Sept. 24, 1918.

Application filed February 17, 1917. Serial No. 149,322.

To all whom it may concern:

Be it known that I, CARL CHRISTIANSON, a citizen of the United States, residing at Deerfield, in the county of Dane and State 5 of Wisconsin, have invented certain useful Improvements in Wagons, of which the following is a specification, reference being had therein to the accompanying drawing.

The invention relates to wagons, and more 10 particularly to the class of self-loading wagons.

The primary object of the invention is the provision of a wagon of this character wherein the body thereof is of novel formation so that the capacity in the loading thereof can be increased or decreased and the extending of the body is automatically controlled and regulated by the operator.

Another object of the invention is the 20 provision of a wagon of this character wherein the body thereof is so constructed that on the filling of the same from a loader the material fed to the body is delivered on to a movable section thereof which is advanced so that the body in its entirety will 25 be completely filled to its capacity, thereby eliminating manual labor in distributing the material, as is usual.

A further object of the invention is the 30 provision of a wagon of this character wherein the movable section of its body is automatically controlled from the power of the traction wheels and said section can be reversely moved for effecting the proper 35 and full loading of the body.

A still further object of the invention is the provision of a wagon of this character which is simple in construction, thoroughly reliable and efficient in operation, strong, 40 durable and inexpensive in manufacture.

Other objects will be in part obvious and in part hereinafter set forth.

The invention accordingly consists in the features of construction, combination of elements and arrangement of parts which will 45 be exemplified in the construction hereinafter described, and the scope of the application of which will be indicated in the appended claims.

50 In the accompanying drawings:

Figure 1 is a top plan view of a wagon constructed in accordance with the invention;

Fig. 2 is a side elevation thereof;

55 Fig. 3 is a vertical longitudinal sectional view through the wagon;

Fig. 4 is a sectional view on the line 4—4 of Fig. 1;

Fig. 5 is a sectional view on the line 5—5 of Fig. 1;

Fig. 6 is a rear elevation of the wagon;

Fig. 7 is a front elevation thereof;

Fig. 8 is an enlarged fragmentary vertical longitudinal sectional view through the gear control.

Similar reference characters indicate corresponding parts throughout the several views of the drawings.

Referring to the drawings in detail, A designates generally a body; B, the supporting truck; C, the front traction wheels and D the rear traction wheels of the wagon hereinafter fully described.

The truck B comprises spaced parallel side rails 10, a front end cross rail 11 and rear end rails 12, the side rails 10 and end rails being fastened to each other in any suitable manner to provide a rigid frame structure. Located below the front cross rail 11 of the truck B are the front running gear bolsters 13 which carry the king bolt 14, and mounted upon one of these bolsters is the front axle 15 supporting the front wheels C, while extending forwardly of the front running gear is the usual draft tongue 16 for the attachment of draft animals, although the tongue 16 can be dispensed with and in lieu thereof a suitable coupling for a traction engine. The front wheels C are of a size to permit the movement thereof beneath the truck B for the effective turning of the wagon, as will be apparent.

The rear axle 17 carrying the rear wheels D is journaled in boxings or bearings 18 fixed to and depending from the side rails 10 of the truck B, and these side rails of said truck have permanently fixed thereto the stationary section 19 of the body A, and this section 19 extends for the full length of the truck, while the movable section 20 is mounted upon and is designed to travel longitudinally upon the said stationary section 19 in the manner presently described and for a purpose hereinafter set forth.

The stationary and movable sections 19 and 20 of the body A carry side boards 21 and incline toward each other, the side boards being supported upon suitable brackets or stanchions 22 which prevent the sagging thereof and rigidly hold the same in place.

Mounted on the rear axle 17 for vertical

swinging movement are gear housings or casings 23 which are elongated and have journaled therein the rack gearing 24 meshing with gears 25 fixed to the rear axle 17, 5 and connected with these housings or casings 23 for unitary movement thereof is an operating mechanism which includes a lever 26 adapted to be manually manipulated by the operator of the wagon for shifting the gear 10 housings or casings 23 for a purpose presently described. Secured to the under side of the movable section 20 in longitudinal alignment with the gearing 24 are rack bars 27 with which are adapted to mesh the outermost 15 gears 24 on the adjustment of the housings or casings 23 for the automatic shifting of the movable section 20 either forwardly or rearwardly at the option of the operator of the wagon. The lever 26 is 20 manually thrown to shift the housings or casing 23 to bring the particular outermost pair of gears into mesh with the rack bars 27 for the shifting of the movable section 20 of the body in the direction desired.

25 The stationary section 19 of the body at the bottom thereof has mounted therein suitable friction rollers 28 which permit the free movement of the movable section 20 when shifted.

30 On the rear end of the stationary section 19 and the forward end of the movable section 20 are racks 29 for sustaining the material when fed to the body of the wagon from a loader of any approved type.

35 The forward portion of the truck B has mounted thereon additional friction rollers 28 for the movable section 20 of the body.

At the front end of the truck B is suitably supported a driver's seat 30 to be occupied by the driver or operator of the wagon. At the front end of the movable section 20 at the corners thereof are depending props or legs 31 which have suitable shoes 32 at their lower ends, which are elevated slightly from the ground and serve to steady the load when the movable section 20 has been shifted forwardly with its load, although it is to be understood that these props or supports can be dispensed with and 50 are only desirable at side hills.

In the use of the wagon the same can be automatically loaded by a loading machine and is designed particularly for the carriage of hay or corn, although any other material can be transported thereby, and in the use of said wagon the necessity of hand loading is eliminated, which requires considerable work or labor as in the hand pitching of the material into the body of the wagon 55 the same has to be distributed in a uniform manner for the proper loading thereof, and in the use of an automatic loader the material delivered therefrom becomes massed or stacked at the rear end of the wagon body 60 so that by reason of the use of the movable

section the wagon body can be loaded expeditiously and with minimum labor.

The stationary section 19 of the wagon body is formed with slots 33 for the proper meshing of the gears 24 in the housings or casings 23 with the rack bars 27 on the movable section of said body, as will be obvious.

It is of course to be understood that changes, variations and modifications may be made in the invention such as come properly within the scope of the appended claims without departing from the spirit of the invention or sacrificing any of its advantages. Each rack bar 27 has in its opposite faces longitudinal grooves in which are loosely 75 engaged L-shaped retaining members which are suitably connected to the rear axle 17, and these members prevent the raising of the movable section 20 when the gears 24 are shifted by the operator, thereby assuring the 80 meshing of the gear with the rack bar and avoiding any possible displacement of the movable section which would interfere with the movement thereof in changing the position of the same. 90

From the foregoing description, taken in connection with the accompanying drawing, the construction and manner of use of the herein described wagon will be readily apparent and, therefore, a more extended explanation has been omitted. 95

Having thus described my invention, I claim:

1. In a wagon, a body formed in two sections one of which is stationary with the other movable thereon, a running gear having a rotating rear axle and on which the body is mounted, a longitudinal rack on each side of the movable section, gear trains having their driving units mounted on the said rear axle, casings angularly movable on the rear axle and supporting the remaining units of the gear trains, each gear train being engageable with one of the racks on the movable section by either one or another of its individual units, and means for effecting the angular movement of the casings whereby the one or the other of these said units of the gear trains is made to mesh with the racks. 110 115

2. In a wagon, a body formed in two sections one of which is stationary with the other movable thereon, a running gear having a rotating rear axle and on which the body is mounted, a longitudinal rack on each side of the movable section, L-shaped retaining members carried by the rear axle and positively but slidably engaging the racks to retain the movable section on the stationary section, casings mounted on the rear axle and angularly movable thereon with the center of said axle as a pivot, a driving gear within each casing and positively connected with the said rear axle, gear trains carried by the casings and driven 120 125 130

by the aforesaid driving gears, two units of each train being engageable one or the other with one of the longitudinal racks, and means for simultaneously effecting the angular movement of the casings, whereby the movable section of the body may be moved in either direction irrespective of the direction of movement of the rear axle. 5

3. In a wagon, a body formed in two sections one of which is stationary with the other movable thereon, a running gear having a rotating rear axle and on which the body is mounted, a longitudinal rack on each side of the movable section, anti-friction rollers uniformly spaced along the stationary section and supporting the movable section throughout the length of its movement, L-shaped retaining members carried by the rear axle of the running gear and positively 15 but slidably engaging the racks to retain the movable section on the anti-friction rollers, 20

casings mounted on the rear axle and angularly movable thereon with the center of said axle as a pivot, a driving gear within each casing and positively connected with the said axle, gear trains carried by the casings and driven by the aforesaid driving gears, two units of each train being engageable one or the other with one of the longitudinal racks, a latch controlled hand lever 30 mounted at the forward end of the stationary section, and connections between the said hand lever and the said angularly movable casings, whereby the one or the other unit of each gear train may be raised to effect its 35 meshing with its attendant longitudinal rack to permit the movable section to be moved rearwardly or forwardly irrespective of the direction of movement of the said rear axle of the running gear. 40

In testimony whereof I affix my signature.
CARL CHRISTIANSON.
